UNITED STATES PATENT OFFICE.

JAMES J. WARD, OF PHILADELPHIA, PENNSYLVANIA, ASSIGNOR TO WARD-MEEHAN COMPANY, OF PHILADELPHIA, PENNSYLVANIA, A CORPORATION OF PENNSYLVANIA.

DESIGN FOR A TOWEL.

47,676.

Specification for Design.

Patented Aug. 3, 1915.

Application filed April 29, 1915. Serial No. 24,833. Term of patent 14 years.

To all whom it may concern:

Be it known that I, JAMES J. WARD, a citizen of the United States, residing at the city of Philadelphia, in the county of Philadelphia and State of Pennsylvania, have invented a new, original, and ornamental Design for a Towel, of which the following is a specification, reference being had to the accompanying drawing, forming part thereof.

The figure is a plan view of the ornamenteally arranged block-like body in color contrast to the raised threads of the towel face and with rose designs displayed therein in relief and with some in color contrast to the raised face of the towel; and the ornamental border ground in color contrast to the raised rose ornamentations therein and corresponding in appearance or effect to similar ornamentations of the towel body face, showing my new design.

I claim:

The ornamental design for a towel, substantially as shown and described.

JAMES J. WARD.
